BOTTLE CRATE.

Application filed May 19, 1926. Serial No. 110,150.

Our invention relates to crates or boxes having compartments or cells for holding bottles and the like, and more especially to crates of this character for carrying and storing milk bottles. Its object is to provide a compartment-forming structure for such crates which is readily manufactured and assembled and installed in the crate, without the use of an excessive amount of material, dispensing entirely with the use of wires or rods which usually heretofore have constituted or made up an important part of such structures; and to provide such a structure in such form that it will have ample resistance against distortion from impacts downward upon it, as by dropping the bottles thereon, yet will be in a high degree yielding sidewise, affording ample adjustment to bottles of varying sizes and shapes due to inaccuracies in manufacture of bottles of the same nominal size, which inaccuracies are practically unavoidable. Other objects will appear in the course of the ensuing description.

We attain these objects by the device illustrated, for example, in the accompanying drawing, in which—

Figure 1 is a general perspective view of a milk-bottle crate embodying our invention, parts being broken away and omitted to reveal the interior construction;

Fig. 2 is a detail perspective view of one of the longitudinal members;

Fig. 3 is a similar view of one of the transverse members;

Fig. 4 is a similar view of parts of a longitudinal and a transverse member, inverted, further illustrating their relation where they cross each other;

Fig. 5 is a similar view of one of the transverse members, partly formed, further illustrating the formation of the members; and

Fig. 6 is a similar view of one end part of one of the members, illustrating certain modifications.

The crate, as is usual in the art, comprises side walls 1 and end walls 2 suitably secured together at their ends, forming corners, which are preferably reinforced in any suitable manner, as by inside corner strips 3 and

outside corner strips 4, and having at their tops suitable stacking guides 5. These details may be as herein illustrated, or may be any one of a number of kinds of corner constructions known in the art; and are not involved in our present improvement. These corner devices usually are of sheet metal, and the walls 1 and 2 are of wood; the end walls 2 having apertures near their tops to afford hand holds. Also, as is known in the art, near the open bottom of the structure thus formed, wires or rods 6 extend from one end wall 2 to the other, with their ends fastened in these walls, on which wires or rods the bottoms of the bottles rest; and, as here shown, these rods are reinforced at the middle of the length of the crate by a strip 7 through which the rods extend, and which has its ends bent sidewise, forming ears 8 to rivet to the side walls of the crate, one of these ears being shown in Fig. 1. These details are described and shown merely to make up, with our present improvement, a complete illustration of a crate in which it is embodied; and our invention is not limited to the accompaniment of these specific details.

The compartment-forming structure here illustrating our invention is designed to form twelve compartments, each to hold a bottle, jar or the like, in three rows of four each, lengthwise of the crate; there being two of the supporting rods 6 under each row. This structure involves the use of two longitudinal members 9 and three transverse members 10; each member presenting laterally in each direction short segmental extensions 11, one at each compartment. The two middle compartments at each side, and the one middle compartment at each end, lack such segmental extensions next to the crate walls 1 and 2, respectively; the structure being so proportioned that when the bottle fits snugly between the three extensions 11 afforded for these compartments, its fourth side will be in tangential contact with the wooden wall of the crate. Similarly, each corner compartment is afforded only two such segmental extensions 11; and the bottle contacts with two of the walls adjacent the crate

corner. Where inside corner strips, such as the strips 3, are used, these are not allowed to extend far enough to be contacted by the bottles in the corner compartments.

5 The longitudinal members all are alike; and the transverse members all are alike and different from the longitudinal members, in addition to having only three instead of four sets of segmental extensions 11, in having 10 notches 12 opening upwardly between sets of extensions 11, whereas the longitudinal members have the notches 13 opening downwardly. Thus, the members 9 and 10 inter- 15 engage where they cross, each entering a notch of the other. The segmental extensions 11 are short enough so that those of the members 9 do not meet those of the members 10, leaving considerable spaces between the extensions at their corners; yet the 20 extensions of both members are so curved that, in any one compartment, they conform substantially to a circle which approximately is that of the circumference of the bottle to be held. Thus, though each segmental extension 25 is considerably less than one-fourth of a circle, owing to their distribution around the compartment, they form, in effect, an embracing holder for the bottle.

Moreover, these extensions 11 are formed 30 by relatively thin sheet metal bent, first, out in both directions at right-angles from the crossing portions of the members 9 and 10, and then curving inward toward each other. Thus, these extensions are yielding to side- 35 wise pressure from the inserted bottles; the curved portions 14 deflecting inwardly of the member and the end portions 15 being drawn somewhat toward each other under this strain. Additional sidewise adjustment 40 is afforded by making the notches 12 and 13 of the members 10 and 9 considerably wider than the part of a member extending therethrough; as is best seen in Fig. 4. Thus, any one of the members 9 and 10 may deflect 45 as a whole, from end to end, in addition to the deflections of the individual extensions 11. Furthermore, we prefer to attach these members 9 and 10 to the crate walls 1 and 2 by means of ears 16 extending 50 up from the longitudinal center lines of the members, with holes 17 in the same alinement, through which rivets 18 pass into the crate walls 1 and 2. By this connection of the ends of the members to the walls, and as 55 permitted by the widening of the notches 12 and 13 as just noted, each member 9 or 10 can swing sidewise in either direction, in addition to the deflections just described. In the modification of Fig. 6, the ear 16' is 60 formed by bending one side of the member 9' sidewise, so that its rivet opening 17' is not alined with the member as a whole; but even this arrangement will permit some sidewise swinging, although the swinging will 65 be partly upward and downward. Either

this formation, or the first described, which is preferred, for the terminal ears of the members, may be employed throughout the structure, for all the members.

The preferred manufacture of the members 9 and 10 may be better understood by reference to the illustration of the partly formed member 10 in Fig. 5. First, the sheet metal blank has been formed of a flat, oblong strip with narrower extensions at its ends, to form the ears 16, with the ear openings 17 therein; and longitudinal slits 19 are formed in this strip at intervals along its center line. Being one of the transverse members 10, transverse slots are formed in 75 the strip midway between the slits 19, to form the notches 12. The areas alongside the slits 19 then are formed up, all in the same direction, forming the right-angle portions 15 for the ends of the extensions 11, 80 and the intermediate curved portions 14 of these extensions. This is the stage of formation shown in Fig. 5. This formation then is folded along its longitudinal center line, downwardly from the position shown 85 throwing the extensions 11 out from each other, until the intermediate portions between the extensions, having the slots cross-wise, form narrow deep channels, with the slots forming the notches 12, out through 90 the junction edge of the channel, which is to be placed in the crate assembly with its open side downward and these notches upward. From the outer end of each terminal slit 19, the folding of the strip is diverged as indicated by the dotted lines 20 at the left end 95 of Fig. 5, to the junction corners of the adjacent ears 16, so that the channel formation flares somewhat to have a wide top, along 100 the end of which the ear 16 is bent upward. 105

The formation of a longitudinal member 9 is the same as that described, except that instead of interior transverse slots to form notches 12, slots are formed in the opposite edges, at the same relative locations, to form 110 the notches 13, which will open out through the bottoms of the members when they are assembled with the open edges of their channel formations downward. And of course, as here shown, these members 9 are 115 longer, and have four formations for extensions 11, instead of three as in the member 10. To form the modified ear 16' of Fig. 6, the ear extension, instead of being at the middle of the end of the oblong blank, is 120 formed at one side; merely one corner portion of the blank being cut away. This avoids the flaring formation of the channel; but such formation, for a centrally alined ear, is not particularly difficult, and is to be 125 preferred, for the reasons before noted. Another modification also shown in Fig. 6, but not dependent upon the modified ear formation there shown, is a lengthening of the slit 19' in proportion to the length of the exten- 130

sion 11', so that adjacent parts of the intermediate channel formations are cut away along the fold. This affords additional flexibility to the extensions while only slightly 5 weakening the channel portions. This modification may be applied to all of the members, with either kind of ear formation.

It will be seen that almost all of the metal in the structure is disposed with its edges up 10 and down; the best disposition of material in a beam-like member, to resist vertical strains and impacts. These are the most severe stresses on such a structure, as the users of the crates often drop bottles onto the interior structure, which, when filled with milk or other contents, are rather heavy. The wires mostly used heretofore are bent down by such blows; and as they can turn where they are secured in the crate walls, they present their bent portions sidewise, reducing 15 the widths of the compartments. This especially occurs after a wire has been bent in two directions, by successive blows, having turned partly between blows, so as to be in 20 the shape of a crank, unavoidably presenting a sidewise distortion. Further, such wires have to have some kind of support at the middle of the crate, which generally reduces their yielding sidewise, yet does not safely 25 guard against their distortion as just noted. Also, to keep the bottles from tilting, two sets of wires, one above the other, are generally needed. Where sheet metal interior compartment-forming structures have been 30 provided, reinforced by wires or rods, these latter practically nullify whatever yielding properties the sheet metal may have had in itself. It will be seen that we so dispose the sheet metal that it is self supporting, is 35 deep enough to prevent tilting of the bottles, with only one tier of compartment-forming means, and therefore makes wire reinforcements unnecessary; and owing to its laterally yielding nature, adjusts itself to odd 40 sized bottles, and is not liable to serious distortion by the ordinary impacts incident to use.

Having fully described our invention, what we claim as new and desire to secure 45 by Letters Patent is:

1. In a bottle crate, in combination with side and end walls, partition members each having segmental lateral extensions, each extension substantially less than ninety degrees 50 in length and disposed substantially symmetrically to a center line at right angle to the length of the member, each member being relatively deep and transversely thin between said extensions and crossing each other 55 between the extensions and having connections at its ends to respective walls of the crate.

2. In a bottle crate, in combination with side and end walls, laterally flexible partition members each having segmental lateral 60

extensions and having notches between the extensions and crossing each other, each within a notch of the other, said notches being substantially wider than the parts of the members crossing therein, allowing lateral flexing of the members. 70

3. In a bottle crate, in combination with side and end walls, partition members each having segmental lateral extensions and having notches between the extensions and crossing each other, each within a notch of the other, said members having offset end parts connected to the respective walls to allow lateral swinging of the members, said notches being substantially wider than the parts of the members crossing therein, to allow said swinging. 75

4. In a bottle crate, in combination with side and end walls, partition members each formed of sheet metal with relatively deep 80 transversely thin segmental lateral extensions and relatively deep narrow cross-sections between the extensions whereby the extensions and the members from end to end are laterally flexible but vertically relatively 85 rigid, said members having notches in the narrow parts between the extensions, and crossing each other, each within a notch of the other, and said notches being substantially wider than the parts of the members 90 crossing therein, and said members having vertically offset end parts pivotally connected to the respective walls, whereby the members may swing laterally to the extent permitted by the relative widening of said 95 notches. 100

5. In a bottle crate, in combination with side and end walls, partition members each formed of sheet metal with relatively deep 105 transversely thin segmental lateral extensions and relatively deep narrow channel formations between the extensions, and having notches in the channel formations and crossing each other, each within a notch of the other, said notches being substantially 110 wider than the parts of the members crossing therein, and said members having laterally flaring terminal channel formations with ears bent vertically from and median to said terminal formations and pivotally connected to the respective walls. 115

6. A partition member for a bottle crate having segmental lateral extensions, each extension substantially less than ninety degrees 120 in length and disposed substantially symmetrically to a center line at right angles to the length of the member, and said member having longitudinal channels alternating with the extensions, and having notches between said extensions in the respective 125 channels.

7. A partition member for a bottle crate, formed of a strip of sheet metal with tongues on its ends and with median longitudinal slits at intervals of its length, bent trans- 130

versely in opposite directions alternately near each end of and within the length of each slit, forming extensions, curved in the middle part of each extension to form concave faces on the extensions, and folded longitudinally on the alinement of the slits, forming channels between the slits and at

the ends, with the extensions facing in laterally opposite directions, and having said tongues bent at an angle to the body of the member formed by said channels and extensions.
